CLAIM

The ornamental design for a mounting bracket and a combination of a mounting bracket and a sensing module, as shown and described.

DESCRIPTION

(73) Assignee: **ITT MANUFACTURING ENTERPRISES LLC.**, Wilmington, DE (US)

FIG. 1 is a top front perspective view of a mounting bracket according to a first embodiment of the present invention; FIG. 2 is a bottom front perspective view of the mounting bracket shown in FIG. 1; FIG. 3 is a side view of the mounting bracket shown in FIG. 1;

(***) Term: **14 Years**

FIG. 4 is a corresponding side view (from the other side) of the mounting bracket shown in FIG. 3;

(21) Appl. No.: **29/516,282**

FIG. 5 is a top view of the mounting bracket shown in FIG. 1; FIG. 6 is a bottom view of the mounting bracket shown in FIG. 1;

(22) Filed: **Jan. 30, 2015**

FIG. 7 is a front view of the mounting bracket shown in FIG. 1; and

(51) LOC (10) Cl. **10-04**

FIG. 8 is a back view of the mounting bracket shown in FIG. 1.

(52) U.S. Cl.

FIG. 9 is a top front perspective view of a combination of the mounting bracket shown in FIG. 1 with a sensing module attached thereto, according to a second embodiment of the present invention;

USPC **D10/60**; D8/381

FIG. 10 is a bottom front perspective view of the combination shown in FIG. 9;

(58) **Field of Classification Search**

FIG. 11 is a side view of the combination shown in FIG. 9;

USPC D8/354, 380, 381; D10/60
CPC Y10S 248/00; Y10S 248/904; Y10S
248/917; Y10S 248/918; Y10S 248/919;
Y10S 248/92; Y10S 248/921; Y10S 248/922;
Y10S 248/923

FIG. 12 is a corresponding side view (from the other side) of the combination shown in FIG. 9;

See application file for complete search history.

FIG. 13 is a top view of the combination shown in FIG. 9;

(56) **References Cited**

FIG. 14 is a bottom view of the combination shown in FIG. 9; FIG. 15 is a front view of the combination shown in FIG. 9; and,

FIG. 16 is a back view of the combination shown in FIG. 9.
